UNITED STATES PATENT OFFICE.

HARRY E. LAKE, OF BOSTON, MASSACHUSETTS, ASSIGNOR TO LAKE OIL BURNING COMPANY, A CORPORATION OF MASSACHUSETTS.

OIL-BURNING DEVICE.

Application filed January 24, 1924. Serial No. 688,295.

My invention relates to that type of device particularly adapted for burning crude, or heavy oil wherein, a "spinner cup," so called, is employed to convert the flow of oil into a thin film and project the film into a blast of air or steam which will atomize the oil so that it may burn freely. It has been the special object of my invention to provide an improved form of spinner cup which shall more effectively assist in the process of atomizing the oil. Also to provide an improved fan or blower. These and further objects of my invention are hereinafter described and claimed.

15 My device may be best understood by reference to the accompanying drawings in which—

Fig. 1 is a side elevation showing the external appearance of the burner with motor 20 and bracket.

Fig. 2 is a side view of the parts shown in Fig. 1 with the bracket, fan and oil distributing parts shown in cross-section.

25 Fig. 3 shows in longitudinal cross-section an enlarged view of the spinner cup and oil nozzle.

Fig. 4 is a cross-section on line 4—4 of Fig. 3.

Fig. 5 is a cross-section on line 5—5 of Fig. 3.

Fig. 6 is a view on line 6—6 of Fig. 2, viewed in the direction indicated by the arrow.

Fig. 7 is a view on line 7—7 of Fig. 2 viewed in the direction with the baffle-plate partly cut away to show the curved baffle-pins attached to the forward face of the baffle-plate.

Fig. 8 is a view on line 8—8 of Fig. 2 viewed in the direction indicated by the arrow, with the diaphragm partly cut away to show the fan blades.

Fig. 9 is a rear view of the fan casing and bracket.

45 Referring now more specifically to the drawings 1 is a bracket provided with a forwardly extending base portion 2. The bracket 1 supports an electric motor 3, the shaft 4 of which is in two parts united by a flexible coupling 5. An enlarged portion 6 of shaft 4 separates the rear ball-bearing 7 and the front ball-bearing 8, which bearings support the fan casing which is mounted on hubs 9 and 10 in the following described manner; projecting forwardly from

the hub 9 is an integral web 11 shaped like the frustum of a cone and provided with air inlets 12. Integrally connected with the outer edge of the periphery of web 11 is the rear portion 13 of the fan casing. The hub 10 has integral therewith an annular spider 14 (see Fig. 6) provided with integral radial arms 15. This spider 14 is provided with holes 16 through which may pass screws which secure the forward portion 17 of the fan casing. The peripheries of the portions 13 and 17 of the fan casing are secured together by means of screws 18. An outer nozzle casing 19 provided with an annular flange 20 is also attached to the spider 14 by means of the same screws which pass through holes 16. The bottom of the fan casing is provided with a lug 21 which may rest upon the extension 2 of the bracket 1. A lug 22 is cast integral with the rear portion 13 of the fan casing, and a screw 22, passing through the opposite portion of bracket 1 and entering lug 22, securely holds the fan, motor and burner to the bracket 1 in a manner whereby they may be readily removed.

An annular air-shutter 24 overlies the slotted web 11. This air shutter 24 is provided with slots or openings which may be brought into or out of register with the slots 12 in the web 11 by revolving the air-shutter 24, one end of which is loosely supported on the hub 9 and the other end of which is provided with an annular flange 25 which fits with firm frictional contact in a groove 26 in the rear part 13 of the fan casing.

The fan is mounted and constructed as follows; fast upon the enlarged portion 6 of shaft 4 is a hub 26 to which is attached an annular plate 27 which is fastened by means of rivets 28 to the fan-blades 29, (see Fig. 8). These fan blades 29 are formed integral with the back plate 30, the outer edge of which runs with slight clearance with respect to an annular lip 31 on the interior of the rear portion 13 of the fan casing. The back plate 30 is provided with an annular flange 32 which runs with slight clearance with respect to a groove in the back portion 13 of the fan casing.

An annular baffle-plate 33 of size corresponding to that of the plate 27 is secured to curved ribs 34 by rivets 35. The ribs 34, which are cast integral with the front portion 17 of the fan casing, are radially

disposed and their inner ends extend as far as the opening in the spider 14 (see Fig. 7).

The nozzle and spinning cups for atomizing the oil are mounted and constructed in the following described manner; the hub 10 (see Fig. 2) is provided with a cylindrical cavity 36 of depth greater than that required to receive the roller bearing 8. Into this cavity 36 is closely fitted the annular flange 37 on 10 the end of the hub extension 38 which is held in place by screws 10^a. The drive shaft 4 passes through the hub extension 38 and has fast on the end thereof a nozzle-cap 39 which has a rearwardly extending tube portion 40. 15 (See Fig. 3.) This rearwardly extending tube portion 40 is provided with a multiplicity of slots 41 which are slantingly disposed as illustrated in Fig. 5. This rearwardly extending tube portion preferably 20 flares somewhat toward the nozzle-cap 39. Surrounding the shaft 4 is a sleeve 42 which fits tightly in the hub extension 38 at one end and at the other end enters loosely a cavity in the nozzle cap 39.

25 The hub extension 38 is provided with a cylindrical cavity 43 within which is mounted by a close driving fit a tube 44 which extends forward for a considerable distance, partly underlying the slots 41 in the tube 30 portion 40 of the nozzle-cap 39. It will be observed that an annular passage is formed between the sleeve 42 and the tube 44. An insulated oil supply pipe 45 is screwed into a cavity in the hub-extension 38 and connects 35 by passage 46 with the annular passage, between the sleeve 42 and the tube 44. This oil supply pipe 45 passes through openings in the annular flange 47 on the spider 14 and the outer nozzle casing 19.

40 The tube portion 40 of the nozzle-cap 39 has a flange 48 to which is attached the outer spinner cup 49. An inner spinner cup 50 is fast mounted at its inner extremity between the outer spinner cup and the tube portion 40 of the nozzle cap 39. It will be observed from an examination of Fig. 3 that there is space between the inner and outer spinner cups and between the inner spinner cup and the tube portion 40 of the nozzle-cap 39. It will also be observed that the cups flare outwardly, the outer cup projecting slightly beyond the inner cup. The outer spinner cup 49 has near its outer rim 55 large openings or slots 51. A sleeve 52, pressed tightly upon the hub extension 38, loosely embraces the rear portion of the spinner cup 49.

An annular casting 53 having a partially tapering bore, as shown in Fig. 2, may be 60 provided to be set in the brick work of the furnace front so as to form a suitable opening through which the nozzle of my device may be thrust to such extent as may be desired to allow sufficient air to enter between 65 the outer nozzle casing 19 and the interior

of the casting 53 to give good combustion.

The operation of my device is as follows: The motor is started, thereby rotating the fan, nozzle-cap and spinner cups, and oil is admitted through the pipe 45. The air shutter 24 is adjusted so as to permit the desired volume of air to enter the system. The fan-blades 28 pass the air outward past their extremities to the channel in the periphery of the fan casing beyond the annular lip 31. (See Fig. 2.) Thence the air passes between the baffle-plate 33 and the front of the fan casing, being directed toward the passages into the outer nozzle casing, between the arms 15 of the web 14, by means of the curved 80 ribs 34. These curved ribs 34 are designed to present a minimum of frictional resistance to the whirling body of air passing between them toward the center of the system by gradually altering the course of the air 85 currents. This has the incidental advantage of reducing the objectionable noise of frictional resistance to air currents as well as minimizing resistance to the flow of the current of air.

90 It will be noted from an examination of Fig. 2 that the space between the fan blades 29 tapers in the cross-section therein shown because of the slanting relation of the plate 30 to the plate 27. Hence as the space between the fan blades 29 widens toward the periphery in one plane, because of the radius disposition of the fan blades, this space 95 narrowed in the opposite plane in a manner whereby the passage between each pair of fan blades maintains a cross-sectional area which is at all points substantially equal. This uniformity results in a well balanced, even flow of air which assists in quiet and efficient operation of the fan.

100 As the rear portion of the fan is sealed on its outer periphery by its close clearance with respect to the annular lip 31, and is also sealed on its inner periphery by the close clearance of the annular flange 32 with respect to the back of the casing, the backward escape of air under the fan pressure is effectively prevented.

105 The oil is atomized in the following described manner; after entering the annular passage 43 between the sleeve 42 and the tube 44, the oil flows forward into contact with the tubular extension 40 on the nozzle-cap 39. As the oil passes through the slots 41 in the tubular extensions 40 the rapid rotation of this part throws the oil outward with great force against the adjacent surface of the inner spinner cup 50. The oil is thus 110 spread in a thin film on the inside of the spinner cup 50 and the rapid rotation of this spinner cup causes the oil to flow outward by centrifugal force along the flaring surface of the cup. Upon reaching the outer rim of this inner cup 50, the film of oil is 115 projected toward the overlying rim of the 120 outer nozzle casing 19 and the interior 125

outer spinner cup 49 and encounters a blast of air issuing through the slots 51, which blast comes from between the outer nozzle casing 19 and the cup 49. This blast of air which has passed through the slots 51 will atomize a large part of the film of oil thrown off the rim of the inner cup 50. A portion of the oil, however, which is thrown off the rim of the inner cup 50 will encounter the rotating rim of the outer spinner cup 49 and will by the centrifugal force imparted by that rim be thrown outwardly across the part of the blast of air issuing from between that rim of the outer cup 49 and the outer nozzle casing 19. This blast of air will complete the atomization of all oil which is thrown into the outer air to the point of combustion.

Heretofore much difficulty has been experienced in getting the oil to spread out in a film upon the spinner cup after an initial filming over had taken place therein. The drops of oil subsequently falling on the oil film tended to retain their globular shape and roll out of the cup without becoming atomized. This would result in imperfect combustion. My device, however, throws the oil first emerging from the source of supply through the slots 41 with such force against the cup that drops are flattened and incorporated in the film. There is no risk that drops of oil will run out along the film and not be thrown as a film from the rim of the inner cup. Moreover, by throwing the oil off the rim of the inner cup in the presence of the air blast and catching the unatomized portion on the rim of the outer cup and again subjecting it to the air blast, I further assure complete breaking up of the oil into fine particles which will burn completely with a hot smokeless flame.

I have stated that my device is particularly designed for use with heavy oils. It may nevertheless be used, with excellent results, with lighter oils, such as kerosene. My device is also useful with water instead of oil in situations where it is desired to atomize water for humidifying purposes in order to humidify the atomizer.

Having thus fully described my invention, what I claim is:

1. In a device of the character specified the combination of a shaft, a casing provided with spaced bearings for rotatably supporting the shaft, a spider at one side of said casing having a hub provided with a cavity to receive one of said bearings, an extension upon said hub having a tube receiving cavity, a tube mounted in the cavity about the rotating shaft and rigidly secured to the extension, a sleeve secured in the cavity about said tube to form an oil passage between the tube and sleeve, an oil inlet for delivering oil to the passage thru a wall of said sleeve, a nozzle-cap secured to

said shaft to be rotated, and having a tubular portion that surrounds and extends rearwardly a substantial distance over said sleeve, said rearwardly extending portion being provided with elongated slots, and a spinner-cup mounted on said rearwardly extending portion and surrounding the nozzle-cap.

2. In a device of the character specified the combination of a fan casing, a shaft rotatably supported by the casing, an annular shutter at one side of the casing and adjustable about the axis of said shaft to control the supply of air to the fan casing, a fan secured to the shaft to rotate in the casing, a spider at the opposite side of said casing, an extension secured to the hub of the spider and having a tube receiving cavity, a tube mounted in the cavity about the shaft and rigidly secured to the extension, a sleeve secured in the cavity, about said tube to form an oil passage between the tube and sleeve, an oil inlet for delivering oil to the passage thru a wall of said sleeve, a nozzle-cap secured to said shaft to be rotated thereby and having a tubular portion that surrounds and extends rearwardly a substantial distance over said sleeve, slots formed in said rearwardly extending tubular portion, and a spinner-cup mounted on said rearwardly extending portion and surrounding the nozzle-cap.

3. In a device of the character specified the combination of a shaft, a stationary member within which said shaft is rotatably mounted, said stationary member being provided with a tube receiving cavity, a sleeve closely surrounding said shaft and passing through said cavity which sleeve is fixed to said stationary member, a tube mounted within said cavity in a manner whereby there is formed an annular oil passage between said sleeve and said tube, an oil inlet entering the passage through a wall of said tube, a nozzle-cap fast mounted on the extremity on said shaft said nozzle-cap having a tubular extension overlying said sleeve and said tube and forming an extension of said passage over the tube, said tubular extension being provided with slots formed through its walls, and a spinner cup mounted on the extension of the nozzle cap and surrounding the nozzle cap, said spinner cup revolving with said shaft, being of substantially frusto-conical form, enlarging toward its outer end and the inner surface thereof being supplied with oil through the slots of the said tubular extension of the nozzle cap.

4. A burner of the class described, comprising a nozzle cap arranged and mounted for rotation and provided with peripheral openings, means to supply oil to the interior of the nozzle cap to be thrown out centrifugally by the rotation of said nozzle cap, an inner spinner cup surrounding said nozzle

cap and the interior surface of which is supplied with oil thereby, an outer spinner cup spaced from the inner spinner cup to form an annular passage therebetween, said outer spinner cup having peripheral openings and said spinner cups being arranged to rotate with said shaft, a fan, and an outwardly contracting outer nozzle through which a blast of air is forced by the fan, said outer nozzle surrounding said outer spinner cup and spaced therefrom so that an outwardly contracting annular passage is formed therebetween through which and through said openings of the outer spinner cup the blast of air is forced and discharged between the outer ends of the inner and outer spinner cup.

5. A burner of the class described, comprising a nozzle cap arranged and mounted for rotation and provided with peripheral openings, means to supply oil to the interior of the nozzle cap to be thrown out centrifugally by the rotation of said nozzle cap, an inner spinner cup surrounding said nozzle cap and the interior surface of which is supplied with oil thereby, an outer spinner cup spaced from the inner spinner cup to form an annular passage therebetween, said outer spinner cup having peripheral openings and said spinner cups being arranged to rotate with said shaft, a fan, and an outwardly contracting outer nozzle through which a blast of air is forced by the fan, said outer nozzle surrounding said outer spinner cup and spaced therefrom so that an outwardly contracting annular passage is formed therebetween through which and through said openings of the outer spinner cup the blast of air is forced and discharged between the outer ends of the inner and outer spinner cup, the length of said outer spinner cup exceeding that of the inner spinner cup and its outer end projecting beyond that of the inner spinner cup, the outer end of the outer nozzle being arranged in close proximity to that of the outer spinner cup.

6. A burner of the class described, comprising a nozzle cap arranged and mounted for rotation and provided with peripheral openings, means to supply oil to the interior of the nozzle cap to be thrown out centrifugally by the rotation of said nozzle cap, an inner spinner cup surrounding said nozzle cap and the interior surface of which is supplied with oil thereby, an outer spinner cup spaced from the inner spinner cup to form an annular passage therebetween, said outer spinner cup having peripheral openings and said spinner cups being arranged to rotate with said shaft, a fan, and an outwardly contracting outer nozzle through which a blast of air is forced by the fan, said outer nozzle surrounding said outer spinner cup and spaced therefrom so that an outwardly contracting annular passage is formed therebetween through which and through said openings of the outer spinner cup the blast of air is forced and discharged between the outer ends of the inner and outer spinner cup, the length of said outer spinner cup exceeding that of the inner spinner cup and its outer end projecting beyond that of the inner spinner cup, the outer end of the outer nozzle being arranged in close proximity to that of the outer spinner cup, the extreme outer end of the outer spinner cup being outwardly flared.

In witness whereof I have hereunto affixed my signature.

HARRY E. LAKE.
